UNITED STATES PATENT OFFICE.

BENJAMIN GREENFIELD, OF BARTLESVILLE, OKLAHOMA.

BOILER-FURNACE.

1,338,438.

Specification of Letters Patent. Patented Apr. 27, 1920.

Application filed October 18, 1919. Serial No. 831,063.

To all whom it may concern:

Be it known that I, BENJAMIN GREENFIELD, residing at Bartlesville, in the county of Washington, State of Oklahoma, have invented certain new and useful improvements in Boiler-Furnaces; and I do hereby declare the following to be a full, clear, and exact description of the invention, such as will enable others skilled in the art to which it appertains to make and use the same.

This invention relates to boiler furnaces and more specifically to furnaces for gas or oil fired boilers.

The operation of oil or gas fired furnaces is influenced by several factors which are not present in the operation of similar furnaces operated by the combustion of solid fuel, and therefore the most effective utilization of different types of fuel requires different types of furnaces. Thus, in burning coal of good quality, the rate of combustion is proportional to the rate at which air is supplied to the coal and may be controlled by varying the draft to the furnace. A large part of the heat of combustion is generated in a glowing bed of fuel and radiated from the glowing fuel directly to the heat transferring walls of the fire box. Any combustible gases generated in the bed of fuel are formed at a temperature near that of the ignition and are completely burned in the fire box immediately above the bed of the fuel before entering the fire tubes of the boiler. The best results are therefore obtained when the coal is introduced directly into the fire box and combustion carried on in direct heat transferring relation to the heat transmitting walls of the boilers. In the combustion of oil, however, the rate and the completeness of combustion are governed largely by the rate at which the fuel is vaporized, and the vapors mixed with air for supporting combustion, since the actual combustion of thoroughly mixed air and vaporized fuel is substantially instantaneous. When the liquid fuel is delivered directly to the combustion chamber of the boiler, similarly to the way in which coal is delivered to coal fired boilers, the combustion of the fuel is affected by local cooling, due to the vaporization of the liquid fuel and by a lack of uniformity in the combustion due to the presence of unmixed or partly mixed gas or fuel. If the rates of feeding oil and air for combustion are increased beyond a certain limit, for the pur-

pose of increasing the capacity of the furnace, the fuel may reach and enter the fire tubes of the boiler before being thoroughly mixed with air and before the fuel is completely burned. As a result, combustion will not be completed and the highest temperature reached until the gases have passed partly or completely through the tubes of the boiler and consequently the full effect of combustion will not be realized. Moreover, the gases may in some cases be chilled by contact with the walls of the fire box and complete combustion will not be obtained. In such cases carbon and tarry substances will be made in the tubes. The capacity and efficiency of oil fired furnaces are therefore limited or determined by the vaporization and the mixing of the fuel with air.

When fuel is injected directly into the fire box, the streams of injected fuel and air tend to form currents, or blasts, which impinge on and overheat parts of the fire box or boiler walls, and thereby injure them. To guard against local burning of the boiler walls in this manner, portions of the walls of the boiler are sometimes lined with fire brick or other heat refractory material. Refractory linings, however, increase the resistance to the transfer of heat into the boiler, and thereby decrease the efficiency of the boiler or furnace. Moreover, the variation in temperature, due to an unevenness in the combustion of the gases caused by the presence of blasts of flame in the fire box, lowers the mean temperature of the fire box, since the maximum temperature obtained cannot be allowed to rise above the point at which the walls of the fire box would be injured.

The primary object of the present invention is to provide a boiler furnace in which a complete and rapid combustion of fluid fuel may be effectively obtained in such a condition that the heat of combustion may be efficiently imparted to the heat transferring surface of the boiler.

Another object of the invention is to provide a boiler furnace for fluid fuels in which the fuel is completely vaporized and intimately mixed with air before combustion and in which combustion is carried on in a zone or chamber unaffected by the vaporization of the fuel.

A further object of the invention is to provide a furnace for an oil fired boiler in which the vaporization and mixing of

the fuel with air and the high temperature combustion of these products is effected substantially out of contact with the metal heat transferring surface of the boiler.

5 A further object is to provide an improved method of burning fluid fuel in fire tube boilers of the locomotive type.

With these and other objects in view, the invention comprises the apparatus described in the following specification and defined in the claims.

The various features of the invention are shown in the accompanying drawings, in which:

15 Fig. 1 is a side elevation, partly in section, of the furnace installation embodying a preferred form of the invention;

20 Fig. 2 is a vertical sectional view of the furnace installation, taken on the line 2—2 of Fig. 1; and

25 Fig. 3 is a horizontal sectional view of the furnace installation, taken on the line 3—3 of Fig. 1.

In the present invention fuel is vaporized, 30 mixed with air and ignited in a sub-furnace, one end of which is placed directly beneath and opens into a fire box of a fire tube field boiler of the locomotive type. Streams of liquid or gaseous fuel and air for supporting combustion are introduced at the front end of the sub-furnace beneath a heated arch which covers that portion of the sub-furnace extending beyond the boiler fire box. The liquid fuel passing under the arch is vaporized by heat radiated from the walls of the arch and sub-furnace, and when it reaches the part of the sub-furnace beneath the fire-box of the boiler, it is thoroughly vaporized and mixed with air. The mixture of air and fuel is ignited by contact with the hot walls of the sub-furnace and passes upwardly through an opening in the sub-furnace into the fire box of the boiler. By the time that the gases have reached the upper portion of the fire box, combustion will have been completed and the gases will be brought to a uniform high temperature. The direction of flow of the gases is changed in passing through the fire box of the boiler, thereby causing eddy currents in the large body of high temperature gases, thus constantly bringing new bodies of hot gases into intimate contact with the heat transferring walls of the combustion chamber before they pass into the fire tubes of the boiler. The walls of the fire box also obtain additional heat by radiation from the walls of the sub-chamber directly beneath the fire box. A part of the heat of combustion of the burning gas in the sub-chamber is also radiated to the arch to supply heat for vaporizing the incoming liquid fuel.

The accompanying drawings illustrate an embodiment of the invention in which a boiler 10 of the locomotive type, designed

for the combustion of coal, is adapted to burn oil or gas. The boiler is provided with a fire box 12 inclosed within the walls of the boiler. To adapt the boiler for burning oil or gas, the fire box 12 is placed directly over the rear end of a sub-furnace 14 in which the liquid or gaseous fuel is vaporized and burned. A stream of liquid fuel from a supply pipe 16 is carried through a nozzle 18 extending through an air inlet pipe 19 by means of a jet of steam admitted through a pipe 20 (Fig. 3). The air pipe 19 and nozzle 18 are mounted in a downwardly inclined position in the front wall of the sub-furnace 14 and are arranged to project the vaporized oil downwardly toward the floor of the sub-furnace beneath a heated ignition arch 21 covering the forward portion of the sub-furnace extending forwardly from the fire box of the boiler. Before passing from below the arch 21, the liquid fuel is completely vaporized and mixed with air which enters through the pipe 19 and through a passage 22 mounted in the front wall of the sub-furnace below the nozzle 18. The nozzle 18 tends to direct the burning fuel against a rear combustion wall 24 of the sub-furnace and the high temperature combustion of the fuel with air takes place in the sub-furnace immediately below the usual ash door opening formed in the bottom of the boiler fire box 12. The air entering through the opening 22 enters into combustion in front of the wall 24 and a very large volume of hot combustion gases is formed in the sub-furnace before they pass up into the fire box 12. The direction of the flow of the air entering through the opening 22 and the liquid fuel and admitted through the nozzle 18 and pipe 19 cause revolving and eddy currents in the combustion gases so that the gases pass into the fire box 12 in currents having a high velocity. The ignited mixture of air and gas is deflected upwardly by the floor and front wall 24 of the sub-furnace and due to this rapid change in direction and the various eddy currents set up, a thorough mixing and equalization of the high temperature of the gases is effected. The burning gases flow upwardly through an opening 28 in the sub-furnace and enter the fire box 12 of the boiler 10. The hot gases are deflected forwardly by the top and rear walls of the combustion chamber 12 and pass forwardly through a number of fire tubes 30 in the boiler 10. By the abrupt change in direction of the flaming gases in the fire box 12, the gases are projected against and brought into intimate contact with the walls of the fire box before passing through the fire tubes 30, and a very rapid heat transfer from the hot gases to the water in the boiler is thereby obtained. The walls of the fire box 12 are also heated by direct radiation of

- heat from the walls of the rear part of the sub-furnace 14. In this manner, the entire surface of the walls of the fire chamber 12 is utilized for the transference of heat and 5 a uniformly high temperature gradient between the interior of the fire box 12 and the water compartment of the boiler is obtained. By completing combustion before the fuel is introduced into the fire box of 10 the boiler, the formation of flames which might play against the tubes or tube sheets of the boiler is avoided and the consequent danger of overheating and burning the walls of the fire box is eliminated.
- 15 The injection of fuel and air into the sub-furnace 14 creates currents or blasts of flame which will heat portions of the sub-furnace to extremely high temperatures before the temperature of the burning gases is 20 equalized by thorough mixing. To prevent the blasts from injuring the walls of the sub-furnace, the sub-furnace is lined with a layer of fire brick 31.

The boiler 10 is supported on its front 25 end by a supporting post 32 and at the rear end by a roller 34 and supporting blocks 36 in such a manner that the rear end moves 31 as the boiler expands and contracts from being heated and cooled. The entire weight of 30 the boiler is supported by the post 32 and roller 34 and none of the weight of the boiler is supported by the sub-furnace or the arch 21. By supporting the boiler in this manner, it is possible to construct the 35 arch 21 so that it will withstand the high temperatures produced in the sub-furnace without the use of stays or other strengthening devices. The boiler surrounding the lower part of the fire box 12 is formed into 40 a mud ring 38 into which sediment may settle from the water compartment of the boiler. To prevent this part of the boiler from being overheated, the inner walls of 45 the mud ring forming the opening 28 are lined with a layer of plastic fire brick 40 which will not be injured by the movement of the boiler caused by expansion or contraction.

In case the boiler may be fired at times 50 with gas, a row of gas nozzles 42 are mounted below the oil nozzle 18. When the furnace is fired with gas, the nozzle 18 and the air inlets 19 surrounding the nozzle 18, are closed and when the oil is used as a fuel, the 55 gas nozzles 42 are closed.

Sufficient air is admitted through the air 60 inlet pipe 19 and the opening 22 to completely burn the fuel in the sub-furnace. The quantity of air supplied through the 65 opening 22 is governed by a sliding damper 44 at the entrance to a passageway 46 leading to the air inlet openings. The position of the damper 44 is adjusted to supply sufficient air for complete combustion of the 70 fuel supplied through the nozzle 18 or 42.

The usual charging door of the furnace is therefore closed to prevent the entrance of any additional air to the fire box, the effect of which would be to cool the hot gases before they come into contact with the walls 75 of the boiler. To prevent the accidental entrance of air direct to the fire box the door frame is usually filled with a wall of fire brick.

With the above described installation, the 75 path through which the burning gases travel is longer than is the case when the fuel is injected directly into the fire box. The combustion of the gases is substantially completed before the gases enter the boiler and 80 all of the surface of the inner walls of the boiler is used for the transference of heat from the hot gases to the interior of the boiler. The velocity and volume of the hot 85 products of combustion may accordingly be increased with a corresponding increase in the capacity of the boiler without danger of overheating or of loss of efficiency.

While the apparatus has been described in connection with fuel oil or gas, it is evident that any fluid fuel or any fuel which is burned in a moving body of gas may be used. In the claims the term "fluid fuel" is therefore intended to include any fuel which is fed into the furnace in a flowing 95 stream and burned in a flowing body of gas.

Having thus described a preferred form of the invention, what is claimed as new is:

1. A boiler furnace comprising a sub-furnace, a heat absorbing and reflecting arch covering the forward part of said sub-furnace, a boiler having a fire box covering and communicating only with the part of said sub-furnace not covered by said arch, and 100 means for introducing fuel and air beneath said arch.

2. In a furnace for a fire tube boiler, a fire box in said boiler, a sub-furnace beneath and opening into said fire box, a heat 110 resisting and radiating arch covering a part of said sub-furnace, and fuel supply nozzles mounted to direct the fuel obliquely downward beneath said arch.

3. In a furnace for a fire tube boiler, a fire box in said boiler, a sub-furnace beneath and opening into said fire box, a heat radiating arch covering part of said sub-furnace, fuel nozzles mounted to direct fuel obliquely downward beneath said arch, and air inlet 120 openings beneath said nozzles.

4. The combination of a boiler, a fire box in said boiler, a sub-furnace having an opening in a portion of its top of a cross-sectional area approximately equal to the inner cross-sectional area of the lower portion of said fire box, said opening communicating with the bottom of said fire box, means for introducing fuel and air into said sub-furnace, means for vaporizing and igniting 125

niting said fuel in said sub-furnace, means in said sub-furnace for maintaining high temperature combustion and mixing said combustion products, and means for protecting said boiler fire box in the vicinity of said high temperature combustion.

5. A boiler furnace comprising a sub-furnace, an arch covering part of said sub-furnace, means for supplying fluid fuel and air to said sub-furnace beneath said arch, a fire tube boiler, a fire box in said boiler positioned over the open portion of said furnace and having a mud ring resting on said furnace and arch, a movable boiler support beneath the fire box of said boiler, and a plastic fire brick lining for said mud ring.

6. In combination with a fire tube boiler, a sub-furnace having a combustion chamber directly under and forming a continuation of the fire box of said boiler, a vaporizing and preheating chamber at one side of and continuous with said combustion chamber, a heat retaining and reflecting covering arch closing the upper part of said preheating chamber, a series of fuel supply nozzles directing the fuel to the bottom of said sub-furnace, and an air supply passage mounted in said sub-furnace below said nozzles.

7. A boiler furnace comprising a sub-furnace, means for supplying fluid fuel and air to said sub-furnace, a fire tube boiler, a fire box in said boiler having a mud ring positioned over said sub-furnace, a roller beneath and supporting the fire box of said boiler and a plastic fire brick lining covering said mud ring and united with said sub-furnace.

8. A method of burning fluid fuel in fire tube boilers of the locomotive type which comprises passing streams of fuel and air

into contact and simultaneously heating and vaporizing said fuel in a refractory heat retaining chamber outside of the fire box of said boiler, igniting and burning said mixture of air and fuel vapor in the chamber, and substantially completing the combustion of said mixture of air and fuel before introducing the hot products of combustion from the chamber into contact with the metal surfaces of said fire box.

9. The combination with a field boiler having an inclosed fire box, of a sub-furnace formed outside of said boiler and having a combustion chamber directly beneath and opening into said fire box, a vaporizing and ignition chamber extending forwardly of said combustion chamber, and means for introducing fuel and air at the forward end of said ignition chamber.

10. The combination with a field boiler having an inclosed fire box, of a sub-furnace formed outside of said boiler and having a combustion chamber directly beneath and opening into said fire box, a vaporizing and ignition chamber extending forwardly of said combustion chamber and means for directing impinging streams of fuel and air rearwardly from the forward end of said ignition chamber.

11. The combination with a field fire tube boiler having an inclosed fire box, of a sub-furnace entirely outside of said fire box, means for introducing, mixing and burning fuel and air in said sub-furnace, and an opening in one end only of the top of said sub-furnace in communication with said fire box for introducing the hot products of combustion directly into said fire box.

In testimony whereof I affix my signature.

BENJAMIN GREENFIELD.
